United States Patent Office.

NAPOLEON SARONY, OF NEW YORK, N. Y.

Letters Patent No. 61,877, dated February 5, 1867.

HOLDER FOR RETOUCHING PHOTOGRAPHIC NEGATIVES.

The Schedule referred to in these Letters Patent and making part of the same.

TO ALL WHOM IT MAY CONCERN:

Be it known that I, NAPOLEON SARONY, of the city, county, and State of New York, have invented a certain new and useful improvement on Frames or Holders for Retouching Photographic Negatives, of which the following is a full, clear, and exact description, reference being had to the accompanying drawing, forming part of this specification, and in which—

Figure 1 represents a view in perspective of a frame or holder, constructed according to my improvement, in its open condition.

Figure 2, a like view of the same closed; and

Figure 3, a transverse vertical section thereof opened or raised.

Like letters indicate like parts throughout the several figures.

My invention has for its object the construction of a frame or holder for securing photographic negatives during the process of retouching them or correcting defects and removing blemishes, and the nature of my invention consists of a sectional main frame, made in two parts, the one of which is hinged to the other along one edge, the lower one being provided with a reflecting interior, and the upper one adjustable to occupy different angles relative thereto, and fitted with a nest of removable independent frames of the necessary sizes and shape to hold different sizes of negatives; such sectional main frame also being provided at its one edge with an outer hinged support, whereby the main frame, when closed for use, without the aid of the mirror, may either be set horizontally or at a slight inclination from the horizon, at pleasure, the whole forming a compact and convenient device for the purposes mentioned.

Referring to the accompanying drawing, A represents the lower section of the main frame, provided internally with a mirror, b, which, when lying horizontally, or thereabouts, and in a proper position relatively to a window in the room, serves to reflect light through the negative arranged to lie in the upper section B of the main frame; the two sections A and B being hinged together, as at c, in order that the upper one may be set to occupy the different angles relatively to the horizon or lower section, in which different positions it is held, as raised, by hinged legs, d, falling into gear with notches or ratched formations, e, arranged along the side edges of the lower section. C C are independent frames or holders, made with grooves or recesses, f, of a size and shape corresponding to the negative designed, in retouching, to be placed therein. These independent frames are fitted to lie snugly one within the other, and constituting a nest of frames of different sizes, corresponding to the usual dimensions of different-sized photographs or negatives, and are made removable, being simply held by buttons or fastenings, g, so that any one or more of such frames may be taken out or inserted according to the sized negative to be secured, and which lies snugly in the recess f of its frame or holder. When it is not required to pass the light through the negative, and during certain manipulations thereof, the sectional main frames A B may be closed, as represented in fig. 2, and the two made to occupy a horizontal position, or set in such closed condition at a slight angle, by falling or lowering a support, h, hinged to the lower section A at its back edge, and which support may be shut up against the edges of the two sections when not required, and so as to be out of the way during a horizontal position of the frames.

What I claim as my invention, and desire to secure by Letters Patent, is—

The combination of the adjustable main frame, sections A B, mirror b, and independent frames or holders C C, substantially as and for the purposes specified; also the combination with the same of the hinged support h, essentially as shown and described.

NAPOLEON SARONY.
